UNITED STATES PATENT OFFICE.

CATHARINE A. GRISWOLD, OF NEW YORK, N. Y.

DESIGN FOR THE ORNAMENTATION OF CORSETS.

SPECIFICATION forming part of Design No. 17,079, dated February 1, 1867.

Application filed December 1, 1866. Serial No. 220,420. Term of patent 14 years.

To all whom it may concern:

Be it known that I, CATHARINE A. GRISWOLD, of the city of New York, county and State of New York, and a citizen of the United States, have invented and produced a new and original Design for the Ornamentation of Corsets, of which the following is a full, clear, and exact description, reference being had to the accompanying drawing, forming part of this specification.

The single figure in the drawing represents in side elevation a corset embodying my new design.

The leading and special feature in my design consists in a series of ornamental bands or stripes on the outward face of the corset, extending along and over said face on the front, side, and rear of the corset from the top edge of the corset, each with a curve toward the waist-line, and with both ends of each band or stripe terminating on said top edge of the corset.

A is a corset, which may be in the usual and ordinary general form shown.

B B' B² B³ represent ornamental bands or stripes, in a series, on the outward face of the corset on the front, side, and rear thereof, extending along and over said surface, each band having a curve from the top edge of the corset toward the waist-line, and with both ends

of each band or stripe terminating at said top edge of the corset. The several curved bands or stripes thus arranged, as shown and described, overlie the upper portion of the corset, one passing around and under the breast-swell on each half of the corset, two extending over the side portion of the corset under the arm, and one being located on the rear of the corset, and the apices of these bands reach to or near the waist-line, as shown. I show four bands or stripes as constituting the series; but the number may be varied, and the apex of each band may be located somewhat below or above the waist-line, without departing from the essential feature of my design.

What I claim is—

The design for a corset herein shown and described, the same consisting of the corset A, having a series of ornamental bands or stripes, B B' B² B³, extending over and upon the outward face of the corset on the front, side, and rear thereof from its top edge, each with a curve downwardly toward the waist-line, and with both extremities of each band or stripe terminating at said top edge of the corset.

CATHARINE A. GRISWOLD.
